(57) **CLAIM**

The ornamental design of a close quarter hack saw, substantially as shown and described.

DESCRIPTION

FIG. 1 is a perspective view of my new design.

FIG. 2 is a top view thereof.

FIG. 3 is a side view thereof.

FIG. 4 is a front view thereof.

FIG. 5 is a rear view thereof.

FIG. 6 is a bottom view thereof.

FIG. 7 is another side view thereof.

FIG. 8 is a perspective view of another embodiment of my new design

FIG. 9 is a top view thereof.

FIG. 10 is a side view thereof.

FIG. 11 is a front view thereof.

FIG. 12 is a rear view thereof.

FIG. 13 is a bottom view thereof; and,

FIG. 14 is another side view thereof.

The broken line showing of the saw blade in FIGS. 1 through 14 and the saw blade support in FIGS. 8 through 14 are included for the purpose of illustrating environmental structure and form no part of the claimed design.

1 Claim, 6 Drawing Sheets
